UNITED STATES PATENT OFFICE.

WILLIAM R. LANDFEAR, OF BROOKLYN, NEW YORK, ASSIGNOR, BY DIRECT AND MESNE ASSIGNMENTS, OF TWO-THIRDS TO BOTTUM & TRECOTT, OF SPRINGFIELD, AND THE EUREKA SILK MANUFACTURING COMPANY, OF CANTON, MASSACHUSETTS.

SILK AND THREAD POLISHING MACHINE.

SPECIFICATION forming part of Letters Patent No. 281,705, dated July 24, 1883.

Application filed January 5, 1883. (No model.)

To all whom it may concern:

Be it known that I, WILLIAM R. LANDFEAR, of the city of Brooklyn, in the county of Kings and State of New York, have invented a new and useful Improvement in Silk and Thread Polishing Machines, of which the following is a specification.

My invention relates to that class of silk and thread polishing machinery in which the silk or thread is wound one or more turns around each of a series of cones, which are supported on pivots, so that they are free to rotate, and which are rotated rapidly as the silk or thread is drawn forward and wound upon spools. In such machines the cleaning or polishing is effected by the rubbing of the silk or thread on itself as it passes around the cones.

The principal object of my invention is to provide a machine for cleaning and polishing thread or silk very thoroughly and rapidly; and my invention therefore consists in various novel details of construction and combinations of parts in machines of that class, hereinafter described and claimed.

The several features of my invention are illustrated in the accompanying drawings, in which Figure 1 represents a side elevation of a machine embodying my invention. Fig. 2 represents a plan thereof. Fig. 3 represents an end elevation thereof. Fig. 4 represents a detail sectional view upon a larger scale, showing the construction and relative arrangement of the cones and their bearings; and Fig. 5 represents a plan of the cone and a portion of one of the rails whereby the cones are supported.

Similar letters of reference designate corresponding parts in all the figures.

40 A designates the end frames of the machine, which are connected by stretchers or longitudinal rails A'.

B designates the driving or main shaft, which is here shown as having at one end fast and loose pulleys B' B'', for the reception of a driving-belt, and at the other end a bevel-wheel, a, gearing into a second wheel, a', on an upright shaft, C.

D designates a carriage, supported at opposite ends by vertical rods D', which are fitted to bearings or guides b in such manner that they and the carriage are free to move vertically. Each of the rods D' is provided with a fixed sleeve or collar, b', on which is a pin or roller, b'', and said pins or rollers rest upon and are acted upon by cams c, placed one near each end of a shaft, E, extending from end to end of the machine. The shaft E carries at one end a worm-wheel, d, which engages with and receives motion from a worm or screw, d', upon the upright shaft C. The shaft E is thereby rotated slowly, compared with the shaft C, and as it rotates its cams c act upon the pins or rollers b'' and impart to the carriage D the rising-and-falling movement necessary for a traverse.

The carriage D carries a number of spindles, e, on which are placed spools e', and to which are secured whisks e''. These spindles are here arranged in two rows, as best shown in Fig. 2, the spindles in each row being opposite the spaces in the other row. In Fig. 1 only a few of the spindles are shown entire, and of the others only the lower portions and the whisks are shown. The spindles are all rotated by a single belt or band, C', which passes around and receives motion from a drum or pulley, C'', on the upright shaft C, as best shown in Fig. 1. In Fig. 2 I have represented the upper board or portion of the carriage D as removed for a part of its length, so as to show the driving-band C' in its passage around the spindles in the two rows.

At the opposite sides of the machine are horizontally-extending boards F, carrying skewers or pins f, on which are placed spools or bobbins f', from which the threads or silk is conducted to the spools e'. The thread or silk, in its passage from each spool or bobbin f', is carried to or through a tension device, G, here shown as consisting of a small cylinder or tube around which the thread or silk is wound one or more times, and which has a hole or opening in its head or end through which the thread or silk is carried. I make no claim to this particular form of tension

any other form may be employed.

The cleaning or polishing of the thread or silk is performed between the tension device 5 G and the spools e', and I will now describe the means employed for the purpose.

Extending transversely to the rails A', and in line with each spool f' and its opposite spool, e', is a bar or rail, H, which in reality

10 forms a part of the frame-work of the machine, and the transverse section of which is shown in Fig. 4. Upon each rail are a number of

15 sockets, g, arranged alternately in two rows, the sockets in each row being opposite the

20 spaces between the sockets in the other row. Referring now more particularly to Figs. 4

and 5, I designate one of the cones around

25 which the thread or silk has one or more turns, and which is free to rotate by the pull on the

30 silk. The cone I is hollow and has a central

35 pivot, h, which fits in a tube, i, secured in the

30 socket by a set-screw, j. The tube i forms

40 a bearing for the pivot h, and as the cone I is

45 hollow said tube can extend up into it nearly

50 to its end. Upon the rail H and adjacent to each socket

55 g are projections or ribs s, which project be-

60 yond the lower edge of the cones, on opposite

65 sides thereof, and prevent the thread or silk

70 from getting around the bearing-tube i below

75 the cone. As here shown, the cones I in each

80 row on each rail H are all arranged with their

85 axes in the same inclined plane, and the axes

90 of the cones in each row are inclined at a re-

95 verse angle to the axes of the cones in the op-

100 posite row. The thread or silk, as it rapidly

105 winds on and unwinds from the cones I, rubs

110 and chafes on itself, and is thereby cleaned

115 and polished, and the arrangement of the cones

at reverse angles effects the cleaning and pol- 40 ishing of the thread or silk all round, and pre- 45 serves it in its round form.

What I claim as my invention, and desire to 45 secure by Letters Patent, is—

1. The combination, with a spindle-carriage, 45 mechanism for imparting a rising-and-falling motion thereto, spindles in said carriage, and means for rotating them, of bars or rails ar- 50 ranged transversely to the length of said car- 55 riage, and series of loosely-pivoted cones car- 60 ried by said bars or rails, and around which the thread or silk is to be wound in its passage 65 to said spindles, substantially as and for the 70 purpose herein described.

2. The combination, with a spindle-carriage, 55 mechanism for imparting a rising-and-falling motion thereto, spindles in said carriage, and means for rotating them, of bars or rails ar- 60 ranged transversely to the length of said car- 65 riage, and two rows of loosely-pivoted cones 70 carried by each bar or rail, the cones in the 75 two rows being arranged with their axes at 80 angles to each other, substantially as and for 85 the purpose herein described.

3. The combination of the carriage D, the 65 shaft E, and devices actuated thereby for giv- 70 ing said carriage its rising-and-falling move- 75 ment, the spindles e, provided with whorls e', 80 with the vertical shaft C, the drum C', and 85 band or belt C', mechanism for rotating the 90 shafts C and E, the tension devices G, the rails 95 H, and loosely-pivoted cones I, substantially 100 as and for the purpose herein described.

WILLIAM R. LANDFEAR.
